Flame&Shade 10 ft Cantilever Offset Outdoor Patio Umbrella with Cross Base Stand, first available Dec. 13, 2019, amazon.com [online], [site visited Feb. 1, 2024], Available at URL: <https://www.amazon.com/dp/B08G82G2HG/?th=1> (Year: 2019).*Primary Examiner — Michelle E. Wilson
Assistant Examiner — Caitlin A Laverty(57) **CLAIM**

The ornamental design for a sunshade umbrella, as shown and described.

DESCRIPTION

FIG. 1 is a top perspective view of a sunshade umbrella, showing my new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a bottom view thereof;

FIG. 8 is a top view thereof; and,

FIG. 9 is a partial magnification of FIG. 2.

The broken lines in the drawings illustrate the portions of the sunshade umbrella, which form no part of the claimed design.
